UNITED STATES PATENT OFFICE

JONAS LEONARD SJÖDIN, OF OSTERSUND, SWEDEN

HANGER FOR TOWELS AND THE LIKE

Application filed July 23, 1930, Serial No. 470,069, and in Sweden September 4, 1928.

This invention relates to improvements in hangers and has for its object to provide a device of this kind, in which objects of woven or flexible material, such as towels and the like, may be readily hung up without the use of hanging straps or other devices secured to the object in question.

A preferred form of the invention is illustrated on the accompanying drawings, in which:

Figure 1 shows a top view of the hanger. Figure 2 exhibits a front view of the invention and Figure 3 a side elevation in section.

The hanger consists of an elastic metal wire, 15 bent into an S-shaped sling 1, one end of which has an elongation 2 which is bent so as to form a member parallel to the middle part 1¹ of the S and located close to said middle part. The elongation 2 extends to 20 the part 5 of the sling and is bent over the sling and provided with a portion 3 extending downward and being driven into a holder 6, serving for a number of hangers. The opposite end 4 of the metal wire sling is secured 25 to the holder in a similar manner.

In order to securely hold the objects in question the middle part 1¹ of the sling and the elongation 2 form a clamp the two squeezing parts of which are free to move a trifle 30 with relation to one another, the spring force and consequently the squeezing action being practically constant along the length of the gripping member.

The cross part 5 of the sling is free to perform a slight movement longitudinally in the bend 3 of elongation 2, being guided on the other side by the holder 6 in such a manner that the squeezing member 1¹ is movable parallel from a position close to member 2 along 40 the whole of its length.

The fixtures 3 and 4 of the hanger may be shaped to suit any possible requirement concerning the location of the hanger either secured directly on a wall or fixed on a holder 45 secured to the structure, wherever the hanger is to be used. The ends of the metal wire, forming the fixtures of the hanger, may thus be bent to one side or the other, or else they may be formed as suitable straps or the like. 50 They may also be carried loosely through the

holder and constructed so as to admit the clasping of the hanger close to the holder, when not in use, the hanger being easily brought into working position, when the holder is hung up on the wall.

Having now described my invention, what I claim is:

An article of manufacture, comprising a unitary metallic member having four legs disposed in a single vertical plane, said legs forming a pair of loops disposed side by side and each having a leg in juxtaposition with a leg of its companion loop, one of said loops being shiftable laterally for the reception of an article to be clamped between said juxtaposed legs, the opposite ends of said member being adapted to engage a suitable support.

In testimony whereof I have signed my name to this specification.

JONAS LEONARD SJÖDIN.
